BLASTING SHELL AND FIRING MECHANISM
THEREFOR

Kenly C. Bugg, Fort Wayne, Ind., assignor to
Materials Blasting Company, Inc., Fort Wayne,
Ind., a corporation of Indiana

Application January 4, 1950, Serial No. 136,769

7 Claims. (Cl. 102—25)

1

This invention pertains to blasting shells and firing mechanism therefor.

In blasting operations of many kinds it is usual to drill holes in the wall to be blasted and to insert some means for breaking out the wall adjacent the holes. As used herein "wall" is considered as a generic term as it is well known that coal or other minerals may be broken out in chunks, as well as wells formed, ditches and ponds blasted, stumps removed, etc. In so doing it is sometimes desirable to break out the material in the wall in chunks (as distinguished from pulverizing the material), and so the blasting means should be a controlled and controllable one. Also, the work must be done with the maximum of safety to the operator.

It is, therefore, an object of this invention to provide means for blasting coal or the like, with the greatest possible safety factors.

Another object of the invention is to provide means of blasting wherein a blasting shell is used which is a self-contained, readily reusable operative device.

Another object of the invention is to provide blasting means wherein the explosive and expansion power of the shell is utilized to the greatest degree in heaving the coal or the material to be mined, rather than in shattering the material.

Another object of the invention is to provide a shell wherein pressure can be obtained of such high value that the shell size and weight may be reduced appreciably.

Another object of the invention is to provide a blasting shell wherein means is incorporated to diminish the hazard of flashing adjacent gases, etc. to a minimum.

Another object of the invention is to provide a blasting shell wherein restriction of velocities of the generated gases can be used in a wide range of blasting power.

Another object of the invention is to provide a shell that may be loaded or positioned in the shooting cavity with flexible and removable means of attachment to control the firing of said shell.

Another object of the invention is to provide a blasting shell wherein means of compression is made an integral part of the shell in its operation.

Another object of the invention is to provide a shell wherein excessive pressures may be built up and controlled that are not readily or practically obtainable by pneumatic compression means and the like.

Another object of the invention is to provide a blasting shell of such high pressure that the diameter of the shell may be reduced to a mini-

2

mum which greatly reduces the cost of drilling in such blasting operations.

Another object of the invention is to provide blasting means wherein the multiple requirements of blasting forces may be regulated and calibrated to the best possible results.

Another object of the invention is to provide blasting means wherein a great area of controlled explosive force may be imparted to the bore area of the hole to be blasted.

With these and various other objects in view, the invention consists of certain novel features of construction and operation as will be more fully described and particularly pointed out in the specification, drawings and claims appended hereto.

In the drawings, which illustrate embodiments of the device and wherein like reference characters are used to designate like parts—

20 Figure 1 is a fragmentary, sectional elevation through one form of blasting shell device embodying the invention;

25 Figures 2 and 3 are fragmentary, sectional elevations through modified forms of blasting shell devices embodying the invention;

Figure 4 is a transverse, sectional elevation taken substantially in the plane as indicated by the line 4—4 of Figure 3;

30 Figure 5 is a transverse, sectional elevation taken substantially in the plane as indicated by the line 5—5 of Figure 3;

Figure 6 is a fragmentary, sectional elevation through another modified form of blasting shell device embodying the invention;

35 Figure 7 is a transverse, sectional elevation through the modified form of blasting shell device embodying the invention shown in Figure 6, the same being taken substantially in the plane as indicated by the line 7—7 of Figure 6;

40 Figures 8 and 9 are transverse sectional elevations corresponding to Figure 7 through other modified forms of blasting shells embodying the invention, the modification shown in Figure 9 showing an added part;

45 Figure 10 is a transverse, sectional elevation of another modified form of reed adapted for use in connection with the blasting shell devices illustrated in Figures 6 to 9, inclusive;

50 Figure 11 is a fragmentary, sectional elevation of one form of firing mechanism adapted for use with the blasting shell devices illustrated in Figures 1 to 10, inclusive;

55 Figure 12 is a fragmentary, sectional elevation through one end of the shell handling tube adapted for use with the firing mechanism and

shell devices illustrated in Figures 1 to 11, inclusive, and 13 and 14, the same showing the connecting end therefor;

Figures 13 and 14 are fragmentary, sectional elevations through modified forms of firing mechanisms adapted for use in connection with the blasting shell devices illustrated in Figures 1 to 10, inclusive;

Figure 15 is an enlarged sectional elevation through another form of blasting shell device embodying the invention, being particularly adapted for use where high compression is desired; and

Figure 16 is an enlarged sectional elevation through yet another form of blasting shell device embodying the invention, being particularly adapted for use where low compression is desired.

Referring first of all, more particularly, to the blasting shell device illustrated in Figure 1, the shell device comprises the body member 20 threaded as at 22 for the reception of mating threads of firing mechanism to be later described, the body member being provided with the shell receiving bore 24 adapted to receive the explosive or pressure generating (blasting) shell 26, said bore flaring to communicate with the pressure cavity 28, which in turn is constricted adjacent the opposite end to communicate with the smaller bore 30. Bore 30 in turn is adapted to communicate with pressure control means to be later more particularly described. The body member 20 is externally threaded as at 32 for the reception of mating (internal) threads of the pressure directing shell nose member 34, the threaded connection between said nose and body member being preferably of the quick disconnect or fast opening type.

Nose 34 is provided with the escape cavity or chamber 36 communicating with the backwardly directed (generally radially disposed) passages 38, and the nose is provided with suitable (internal) threads 40 for the reception of mating (external) threads of the end closure 42, the threads between the end closure and nose being preferably of the fast opening type. Nose 34 is shouldered at 44 for the reception of the hardened insert 46, said insert being provided with the shaped bore 48-50 which is adapted to retain the shaped bullet, projectile, or expellable closure member 52. As shown, the bore 48-50 is smaller adjacent the center of the insert than at the ends, that is, the bore may be said to be made up of oppositely directed frustoconical parts 48 and 50 flaring away from the center of insert 46. The projectile is correspondingly shaped. The passage 48-50 communicates with cavity 38 whereby the projectile may pass through said cavity and be received within the cavity 54 provided in the closure 42. In order to pressure seal nose 34 to body 20 and the nose to insert 46, suitable O-rings 56 are interposed between the end of body 20 which is received within the securing end of nose 34, and nose 34, and between nose 34 and insert 46.

In the operation of this form of the device the pressure generating (blasting) shell 26 is of the selective capacity depending upon the particular use to which the blasting shell is to be used. The body member 20 is inserted the predetermined distance into the bored hole of the material (such as coal) to be displaced. The shell 26 is fired or detonated such as in a manner and by the means to be later described, which causes the predetermined pressure to be built up within the chamber of the pressure cavity 28. When

the predetermined pressure is built up within said cavity, the projectile 52 is caused to be expelled from the hardened insert 46, passing into the cavity 54, thus permitting the pressure built up within the cavity 28 to be released suddenly through passages 38, in effect, blowing back toward the entrance of the bore in which the body member is inserted. Thus it may be said that the displaced material is suddenly moved due to 10 subjecting it to the concentrated velocity of the expanding gases released by firing shell 26. This release of pressure at high or concentrated velocity through passages 38 causes a restriction of velocity against the material defining the bore which effects a controlled heaving action 15 against said material of the bore whereby the material is dislocated in large chunks without pulverizing, and, as it is controlled, with safety to the location of the blasting.

After the blasting shell device has been used as by exploding the explosive shell 26, it can be removed for additional use, a new shell 26 being applied in cavity 24, the nose 34 being removed and end closure 42 being removed, the socket 58 being formed in said end closure to facilitate removal. Upon removal of end closure 42 the expended bullet 52 can be removed and a new bullet 52 can be applied to the insert 46, or a new or loaded insert 46 can be applied, after which the nose and end closure can be assembled with the body member for use as above described.

In the construction illustrated in Figure 2 the body 60 is similar to body 20, the cavity 62 is similar to cavity 28 and communicates with passage 64, which is similar to passage 38. The end of body member 60 is provided with the external threads 66 for the reception of complementary threads of the pressure directing shell nose member 68, a suitable seal ring 70 being interposed between the shell 60 and nose member 68, and seal ring 72 being interposed between nose member 68 and the hardened insert 74 (similar to insert 46). As before, the insert is provided with the reverse tapered bores 76-78 closed by means of the projectile or bullet 80, insert 74 being provided with the shoulder 82 seated on a complementary shoulder in the nose member 68.

As before, passage 78 communicates with the cavity 84 which in turn communicates with passages 86, similar to passages 38, being directed backwardly of the body member 60. Cavity 84 communicates with cavity 88 provided with the bushing 90 forming a stop for shoulder 92 of the piercing and escaping plug 94, shoulder 92 being slidably mounted in cavity 96 defined at its other end by shoulder 98. The sharp end 100 of plug 94 is adapted to move within passage 102 to pierce the cap 104 of the carbon dioxide cartridge 106, or other pressure cartridge for releasing materials reactive to combustible materials. Cartridge 106 is mounted within the cavity 108 and positioned by the pressure screw 110 of threaded cap 111, said screw being adjusted by the socket 112, the end of the cartridge 106 containing cap 104 being seated on washer 114 disposed adjacent the plug 94. Cap 111 is preferably threaded to nose 68 by quick disconnect threads to facilitate changing cartridges 106. Plug 94 is provided with axial passage 116, and radial passages 118 (in the sharp end 100) permitting the passage of the contents of cartridge 106 to cavity 88 in which it can be combined with the pressure fluid expelled from cavity 62, after which the mixture may be passed through passages 86 for displacement of the adjacent coal or other material.

Thus it will be seen that in the device illustrated in Figure 2, when the explosive shell (similar to shell 26, Figure 1) is fired the projectile 80 is propelled to engage the piercing and escaping plug 94 moving it toward the left as viewed in Figure 2. This movement causes the sharp end 100 of plug 94 to pierce cap 104 permitting the gas under pressure in cartridge 106 to be released rearwardly, flowing through passages 118-116 to cavity 88 mixing with the gas released from chamber 62, the mixture flowing through passages 86 to controllably displace the adjacent material of the bore in which the device is disposed. To reuse the device it is only necessary to remove cap 111 and replace cartridge 106, remove nose 68 from body 60 and replace the insert 74 with a new insert and projectile (removing the fired projectile from cavity 88), and replacing the fired explosive shell (as 26 in Figure 1).

In the construction illustrated in Figures 3, 4 and 5, the body 120, similar to body 20, is provided with pressure cavity 122, similar to cavity 28, which communicates with smaller bore 124, the end 126 of body 120 being provided with the external quick disconnect threads 128 adapted to receive cooperating internal threads of the nose 130. An O-ring seal 132 may be disposed between nose 130 and body 120. Nose 130 is provided with the piston bore 134 similar to and communicating with bore 124, said bore 134 communicating with cavity 136, similar to cavity 36, which in turn communicates with the rearwardly directed passages 138.

Bore 134 communicates with resistance fluid reservoir 140, stepped shoulders 142 and 144 being interposed between bore 134 and reservoir 140. The reservoir is closed by means of the fixed closure plug 146 threaded as at 148 into said nose, spanner wrench openings 150 being provided to facilitate the application and removal of the plug 146 with respect to said nose.

Plug 146 is provided with spaced legs defined by suitable openings 152, said legs being substantially of the same width as shoulder 144 and being adapted to seat thereon. Pressure control piston 154 is slidably mounted as at 156 in plug 146, an O-ring seal 158 being provided therebetween to prevent leakage from the reservoir 140 past the piston 154. An O-ring seal 160 is also provided between the nose 130 and plug 146 to prevent leakage from said reservoir 140, the piston 154 being provided with the shoulder 162 adapted to seat upon shoulder 142 when the plug is in its innermost position wherein the closure member, plunger or cylinder 164 is in position to close communication between the passages 138 and bore 134. O-ring seals 166 are preferably disposed on each side of the passages 138 to prevent leakage past the closure member 164 to passages 138.

Shoulder 162 is provided with a plurality of slots or small passages 168 forming by-passes which regulate the speed travel of piston 154. When the piston 154 is in the position illustrated in Figure 3, that is, when shoulder 162 is seated on shoulder 142, rearwardly directed passages 170 filled with resistance fluid are closed at their outer ends. Said passages 170 communicate with an axial or centrally disposed passage 172 closed by means of the ball valve 174 seated on seat 176. In this position passage 172 and passages 170, filled with resistance fluid, are closed against communication with radial passages 178 which communicate with reservoir 140, all filled with resistance fluid, and are also closed against com-

munication with the spring recess 180 also filled with resistance liquid. Spring 182 is disposed in the recess 180 and is seated at one end on the ball valve 174 and at the other end on the closure plug 184 whereby said spring urges said ball valve toward closed position on seat 176.

Closure plug 184 is threaded as at 186 to piston 154 and a suitable socket 188 being provided for the reception of a wrench for removal or adjustment of the plug 184. When the ball valve 174 is in closed position as illustrated in Figure 3, as before pointed out, passage 172 is closed against communication with passages 178, but there is a space 190 around the valve 174 so that passages 178 are in communication with spring recess 180, that is, there is clearance between the ball and the bore of recess 180.

Assuming the device to be as illustrated in Figure 3, it is understood, of course, that the pressure generating shell as 26 is in position as illustrated in Figure 1, and the piston 154 is in position where the plunger 164 closes communication between bore 134 and, consequently cavity 122, and passages 138. Resistance fluid is disposed within the reservoir 140, recess 180, and passages 178, 168, 170 and 172. When the shell 26 is fired the predetermined pressure built up within the cavity 122 moves the piston 154 toward the left as viewed in Figure 3, the resistance fluid resisting movement of the piston 154, but flowing, upon movement of said piston, through passages 168, being displaced by movement of the shoulder 162.

When passages 138 are uncovered, the pressure built up within the cavity 122 is released blowing back toward the entrance of the bore into which the body member is inserted, causing the controlled breaking away of the material adjacent the bore. When the device is to be used again the piston 154 is, or course, moved inwardly to the position illustrated in Figure 3, causing the plug 164 to close passages 138. Movement of the piston 154 is facilitated by the valve 174 which readily opens permitting the resistance fluid to flow from the right of shoulder 162 to the left thereof. A new shell 26 may then be applied into the position as illustrated in Figure 1 whereupon the device is ready for another operation.

Referring now to the blasting shell device illustrated in Figures 6 and 7, said device comprises the shell or body 192 provided with the blasting shell bore 194 for the reception of the explosive or pressure generating shell 196, the body 192 being provided with the threads 198 for the reception of mating threads of the firing mechanism for shell 196. Bore 194 communicates with bore 200 which is divided by means of the spider 202 perforated as at 204. Body 192, for substantially the length of the spider, is provided with longitudinal slots 206 whereby the body adjacent the spider is, in effect, formed of a plurality of substantially triangularly shaped ribs 208.

The end of body 192 beyond the ribs is closed as at 210, and between the ribs 208 suitable shoes or reeds 212 are fitted, the reeds 212 in Figure 7, having an outer arcuate portion 214 and an inner rib 216 fitting within the slots 206. Pressure rings 218 are preferably provided acting as a seal, the outer arcuate portions 214 of adjacent reeds extending toward each other forming an overlap around the outer arcuate surfaces of the ribs 208. The reeds may be secured within the shoulder 220 of body 192 by means of hold-

ing ribs 222 and where the reeds are of rubber or other resilient material, a retaining ring 224 may be applied. If a steel reed is used, ring 224 may be omitted.

In the construction shown in Figure 8, body 192 is similar to that already described with respect to Figures 6 and 7. The reeds 226 are shown as of rubber and the outer flange 228 more closely embraces the ribs 208 of the body, but in this case inasmuch as the reeds are resilient, no seals 218 are necessary between the inwardly projecting rib portion 230 (similar to portion 216) of each reed.

In the construction illustrated in Figure 9, the body portion 192 is formed in a similar manner as described in Figures 6 to 8, inclusive. In this case reeds 232 are a combination of a metallic substance and a resilient substance. For example, the outer reed member or part 234 of each reed is of similar shape to that shown in Figure 8 and may be of metal, and an inner rubber base 236 may be interlocked or otherwise secured as at 238 to the outer reed member 234, and may be resiliently wedged between adjacent ribs 208.

In any of the modifications shown in Figures 6 to 10 inclusive, an outer cylindrical member 248, of any suitable material, may be used to encase the reeds, the material being selected to delay in a predetermined manner, the buckling of the reeds, whereby the tube acts as a timer to increase the velocity of the fluid acting upon the material to be displaced, as the pressure is retained until the desired pressure is reached. Thus it will be seen that the reeds must first burst the tube before acting upon the adjacent substance to be displaced and consequently the pressure must be built up to the selected amount before it is effective to do its work. Reeds of pasteboard, plyboard, light metal, plastic, or the like materials have been found to be satisfactory depending upon the desired use.

In the construction illustrated in Figure 10, a reed 242 is illustrated which is preferably of metal and is shaped similar to that illustrated in Figure 8, but where a metal reed is used, it is desirable to use a rubber O-ring 244 to act as a seal between the reed and the adjacent ribs 208. The flange 246 of this reed closely embraces the adjacent rib 208 as illustrated in Figure 8, the O-ring 244 sealing against the adjacent rib as in the case of rings 218, as shown in Figure 7.

Referring now to the firing mechanism illustrated in Figure 11, said mechanism comprises the body member 248 provided with the external threads 250 adapted to be connected as to threads 252 of shell body 254, threads 252 corresponding to threads 22 or 198 of the shell bodies described in Figures 1 to 10 inclusive, and shell body 254 corresponding to bodies 20, etc. Body 254 is provided with the bore 256 for the reception of the firing shell 258 corresponding to the firing shells 26, etc., already described, said shell being provided with the retaining flange 260 and the detonator or firing cap 262.

Detonator 262 is adapted to be received within a complementary recess formed in insert 264 provided in the end closure member 266 of the bolt releasing member 268, the end closure member being secured as by threads 270 to complementary threads of the body member 248. The bolt releasing member 268 comprises the end closure member 266 and the axially extending cylindrical member 272 provided with spaced slots 274 extending from closure member 266 to the shoulders 276, shoulders 276 being shown as sloping or ex-

tending downwardly and outwardly toward the closure member 266. The inner end of the cylindrical member 272 is closed by the spring seat and closure member 278 secured as by pin 280.

Bolt member 282 is slidably mounted within the cylindrical member 272, being provided with the hammer end 284 and being slotted for the reception of dogs 286 pivoted to said bolt as at 288, and being urged outwardly of slots 274 by means of springs 290. The outer ends of dogs 286 are adapted to be engaged by adjacent shoulders 292 of the cocking bolt 294, said bolt having one end 296 engaging closure 266 and being slidably mounted in bore 298 of body member 248. Spring 300 is interposed between member 296 and shoulder 302 defining bore 298, spring 300 urging the cocking bolt to the position illustrated in Figure 11.

The cocking bolt 294 extends beyond shoulder 302 within bore 304, and a felt washer 306 forms sealing means engaging the bolt 294, being positioned by the C-washer retainer 308. Bolt 294 may be moved from the position illustrated in Figure 11 toward the right as viewed in said figure by means of the chain 310 secured to the closed end of the bolt 294 and a suitable line 312 secured to said chain. Line 312 may extend back any suitable distance and may pass through slot 314 in the shell handling tube 316, or may extend back through said tube. Tube 316 as shown is provided with oppositely disposed slots 314 and the bayonet openings 318 for the reception of securing pins 320 provided in the flared end 322 of the body member 248.

Closure member 266 is provided with the axially disposed recess 324 in which the cylindrical end 326 of the firing pin member 328 is slidably mounted, firing pin 330 being adapted to extend through opening 332 in the closure member 266 for engagement with the detonator 262. A spring 334 is disposed between end 326 and the end of closure 266 urging pin 330 to a position where the cylindrical end 326 is urged toward hammer end 284, that is, to a position where it projects beyond member 266 so it may be struck by the hammer end as it moves from cocked position to firing position shown in Figure 11. Firing pin member 328 is provided with the stem 336 which extends through hammer end 284, and a spring 338 is interposed between seat closure 278 and hammer end 284, urging said hammer end toward end 326 (or closure 266).

Assuming the parts to be in a position as illustrated in Figure 11, that is, with the firing mechanism associated with the blasing shell device, when it is desired to fire the firing shell 258, the cocking bolt 294 is moved toward the right causing dogs 286 to be engaged by shoulder 292 to move bolt 282 toward the right. As the hammer end 284 of bolt 282 moves away from end 326 (and closure 266), spring 334 causes slight movement of the firing pin toward the right as viewed in Figure 11 whereupon end 326 projects within the bolt releasing member, the extent to which it projects being limited by the clearance between the end of stem 336 and closure 278 when the device is in the position shown in Figure 11. Continued movement of the cocking bolt 294 toward the right causes dogs 286 to be depressed inwardly upon engagement with the shoulders 276 thereby releasing bolt 282 permitting spring 338 to act to move said bolt toward the left as viewed in Figure 11. This movement causes the hammer end 284 to strike end 326 causing the firing pin 330 to set off the detonator, with the

consequent operation of the blasting shell device as already described. Release of the cocking bolt 294 will permit the spring 300 to move said cocking bolt toward the left as viewed in Figure 11, whereupon the device again will be in a position for firing. It will, of course, be necessary to disconnect the body member 248 from body member 254 of the shell and apply a new blasting shell 258 for additional firing operation.

In the construction illustrated in Figure 13 the firing mechanism body 340 is provided with the threads, not shown, for connecting body 340 to the blasting shell device, and the body 340 is provided with the flared end 342 for connection to the shell handling tube 316 shown in Figure 12, pins 344 being provided for the bayonet socket connection. In this case the firing shell 346 is provided with the electrical igniter or firing cap 348 and the electrical wiring 350 therefrom passes through a suitable opening 352 in the body 340 and rearwardly as through the shell handling tube illustrated in Figure 12 to the operating switch.

In the device illustrated in Figure 14 a pneumatic firing mechanism is illustrated. In this mechanism the body member 354 is provided with the threads 356 for connection to the blasting shell device and is also provided with the threads 358 for connection to suitable threads of the end closure 360, similar to end closure member 266 (Figure 11). End closure 360 is provided with the recessed insert 362 for the reception of the detonator or firing cap, similar to that illustrated in Figure 11, and is provided with the recess 364 in which the cylindrical end 366 (similar to end 326) is slidably mounted. Spring 368 (similar to spring 334) is disposed in said recess, urging the firing pin 370 toward the right as viewed in Figure 14. The cylindrical end 366 is provided with the stem 372 (similar to stem 336) extending through the bolt 374 and a spring 376 is disposed between the hammer end 378 of said bolt and the closed end of the bolt releasing member 380 (similar to member 268).

Bolt releasing member 380 is provided with the slots 382 having shoulders 384 to engage the dogs 386 pivotally mounted as at 388 to bolt 374, being urged outwardly of slots 382 by means of the springs 390. The ends of dogs 386 are adapted to be engaged by shoulders 392 (similar to shoulders 292) defined at the end of slots of the cocking bolt 394, said bolt being slidably mounted in bore 396 of body 354, a seal ring 398 being provided therebetween. Body 354 is provided with the larger bore 400 and cocking bolt 394 is provided with a rib 402 slidably mounted therein and slidably sealed by means of a seal ring 404. A stop in the form of a C-washer 406 may be disposed in bore 400 for limiting the cocking travel (travel toward the right as viewed in Figure 14) of the cocking bolt 394, and forming a spring seat for spring 407 disposed between said washer 406 and rib 402 for returning said bolt to initial position.

A fluid passage 408 provided in body 354 is adapted to be connected to a suitable fluid pressure line and communicates with bore 400 between rib 402 and shoulder 410 between bores 396 and 400. Thus fluid pressure may be introduced to move the cocking bolt 394 toward the right as viewed in Figure 14 causing the dogs 386 to move the bolt 374 away from cylindrical end 366 of the firing pin. Spring 364 is permitted to cause the cylindrical end 366 to project slightly within bolt releasing member 380. When the

dogs 386 contact shoulders 384, the dogs will be released from the cocking bolt 394 permitting spring 376 to move the hammer end 378 to strike cylinder 366, causing firing pin 370 to actuate the detonator, thus causing firing operation in a manner above described. The device is reloaded as described for the device illustrated in Figure 11, release of the fluid pressure returning bolt 394 to initial position as shown in Figure 11, or spring 407 may be omitted and the bolt returned manually.

In the shell mechanism illustrated in Figure 15 the shell body 412 is provided at its rear end with quick disconnect internal threads 414 adapted to connect with complementary threads 416 of the housing 418 of the firing mechanism indicated generally at 420. Safety ram rod 422 is adapted to be used to position the mechanism in desired position.

The firing mechanism 420 is substantially the same as shown in Figure 11, being provided with the detonating pin closure 424 provided with the passage 426 slidably receiving the detonating pin 428. The closure 424 is threaded as at 430 to the threaded end of the firing mechanism housing 418. Firing pin 428 is provided with the enlarged cylindrical end 432 slidably mounted in the cylindrical cavity 434 of the closure 424.

In inoperative position, that is, when the pin 428 is in engagement with the detonator of explosive shell 436 (prior to firing), the inner end of the cylinder 432 extends slightly within the housing of the firing mechanism where it can be struck by the hammer 438 of the spring loaded bolt 440, said bolt being similar to bolt 282 (Figure 11).

Shell 436 comprises the outer casing 442 which retains the explosive charge 444 and the shell wadding piston 446, the piston being retained by the inturned flange 448 of the casing 442. The bore 450 of the casing 412 is substantially cylindrical as at 452 for a length substantially greater than the length of the explosive shell 436. Thereafter there is a tapered bore portion 454 which extends to substantially cylindrical bore 455 which extends past the rearwardly directed passages 456 to a point where it communicates with a substantially cylindrical bore 458 which is larger than the adjacent end of bore 455, whereby a shoulder 460 is disposed between bores 455 and 458. The end of bore 458 is adapted to be closed by a quick disconnect cap 462 secured to the casing 412 through quick acting threads 464, the cap 462 being recessed as at 466.

In operation of this form of relatively high compression device, when the explosive shell 436 is detonated by the pin 428, the explosive charge 444 causes the piston 446 to move toward the left as viewed in Figure 15. The expanding gases are controlled suitably by movement of the piston 446, the piston moving toward the bore 458 being slowed down by the tapered bore 454. When the piston passes passages 456 compressed gases will be released backwardly through passages 456. Any gases or fluid compressed in front of the piston 446 will bleed past the piston 446 after it has been received in bore 458. The device may be reloaded by disconnecting the body 412 from the firing housing mechanism 420, replacing the explosive shell 436, and the cap 462 may be removed for removal of the piston 446 trapped in bore 458. The device can then be reassembled as indicated in Figure 15 for additionally operation in selected places.

In the device illustrated in Figure 16 the body 468 is provided with the quick disconnect threads 470 adapted to form a connection through complementary threads 472 of the housing 474 of the firing mechanism 476, a safety ram rod 478 being provided for application of the device in selected operative position. The firing mechanism 476 is similar to that illustrated in Figure 11. The end of the housing is closed by means of the closure member 480 in which the firing pin 482 reciprocates, being actuated to fire the explosive shell 484 by means of the hammer 486 of the bolt 488.

The body 468 is provided with the cylindrical bore 490 for the reception of the firing shell 484, said bore communicating with the bore 492 of the body in which the free piston 494 is mounted. Said piston is provided with a seal ring 496 for retarding and controlling movement of the piston in the bore 492. Thus it may be said that an explosion chamber 498 is provided within the bore 492 between the piston 494 and the end wall 500 in which shell bore 490 is disposed. Rearwardly directed passages 502 are provided at a selected part of the body, and the end of said body is closed by means of the quick disconnect cap 504 threadedly secured thereto as at 506, the cap being provided with the compression recess 508.

When the explosive shell 484 is fired, piston 494 is moved toward the left as viewed in Figure 16 compressing any gases or fluid ahead of the piston into the space between the end of the piston and the cap 504. As the piston uncovers passages 502 the fluid pressure behind the piston is directed rearwardly into the bore in which the device is applied. The device may be reloaded by disconnecting the body 468 from housing 474, replacing shell 484 and thereafter reconnecting body 468 and housing 474. The piston 494 may be turned from the dotted line position illustrated in Figure 16 to the full line position illustrated in said figure by removal of the cap 504, after which this relative low compression blasting shell device is in condition for another operation.

It is to be understood that this application is not to be limited by the exact embodiments of the device shown, which are merely by way of illustration and not limitation as various and other forms of the device will, of course, be apparent to those skilled in the art without departing from the spirit of the invention or the scope of the claims.

I claim:

1. In blasting mechanism, the combination of a body member comprising an elongated substantially cylindrical member, said cylindrical member having means at one end for connection to firing mechanism, said body member having a shell bore adjacent said end for the reception of an explosive shell, said body member between said shell bore and the other end being formed of spaced ribs, a spider connecting said ribs, and reed members closing the spaces between said ribs.

2. In blasting mechanism, the combination of a body member comprising an elongated substantially cylindrical member, said cylindrical member having means at one end for connection to firing mechanism, said body member having a shell bore adjacent said end for the reception of an explosive shell, said body member between said shell bore and the other end being formed of spaced ribs, a spider connecting said ribs, reed members closing the spaces between said ribs,

and a frangible cylindrical member embracing said reed members.

3. In blasting mechanism, the combination of a body member comprising an elongated substantially cylindrical member, said cylindrical member having means at one end for connection to firing mechanism, said body member having a shell bore adjacent said end for the reception of an explosive shell, said body member between said shell bore and the other end being formed of spaced ribs, a spider connecting said ribs, reed members closing the spaces between said ribs, and securing means embracing one end of said reed members for securing said end of said reed members to said body member adjacent said shell bore.

4. In blasting mechanism, the combination of a body member comprising an elongated substantially cylindrical member, said cylindrical member having means at one end for connection to firing mechanism, said body member having a shell bore adjacent said end for the reception of an explosive shell, said body member between said shell bore and the other end being formed of spaced ribs, a spider connecting said ribs, and reed members closing the spaces between said ribs, said reed members each comprising an inwardly extending reed rib disposed between adjacent spaced ribs of said body member, seal means between said reed rib and said spaced ribs, and arcuate flanges on said reed rib overlying but spaced from the adjacent spaced ribs.

5. In blasting mechanism, the combination of a body member comprising an elongated substantially cylindrical member, said cylindrical member having means at one end for connection to firing mechanism, said body member having a shell bore adjacent said end for the reception of an explosive shell, said body member between said shell bore and the other end being formed of spaced ribs, a spider connecting said ribs, reed members closing the spaces between said ribs, said reed members being resilient and each comprising an inwardly extending reed rib disposed between adjacent spaced ribs of said body member, and flanges on said reed rib overlying and engaging the adjacent spaced ribs.

6. In blasting mechanism, the combination of a body member comprising an elongated substantially cylindrical member, said cylindrical member having means at one end for connection to firing mechanism, said body member having a shell bore adjacent said end for the reception of an explosive shell, said body member between said shell bore and the other end being formed of spaced ribs, a spider connecting said ribs, reed members closing the spaces between said ribs, said reed members being metallic and each comprising an inwardly extending reed rib disposed between adjacent spaced ribs of said body member, a resilient base on said reed members resiliently engaging the adjacent spaced ribs, and flanges on said reed rib overlying and engaging the adjacent spaced ribs.

7. In blasting mechanism, the combination of a body member comprising an elongated substantially cylindrical member, said cylindrical member having means at one end for connection to firing mechanism, said body member having a shell bore adjacent said end for the reception of an explosive shell, said body member between said shell bore and the other end being formed of spaced ribs, a spider connecting said ribs, reed members closing the spaces between said ribs, said reed members being metallic and

each comprising an inwardly extending reed rib disposed between adjacent spaced ribs of said body member, seal means between said reed rib and said spaced ribs disposed in recesses in said reed rib, and flanges on said reed rib overlying and engaging the adjacent spaced ribs.

KENLY C. BUGG.
